Attorney, Agent, or Firm—Jean H. Dubuc

[57] CLAIM

The ornamental design for an endless vehicle track, as shown and described.

DESCRIPTION

FIG. 1 is a perspective view of an endless vehicle track showing my new design, it being understood that the tread pattern is repeated uniformly throughout the length of the track as shown schematically by solid lines; FIG. 2 is an enlarged top plan view thereof; FIG. 3 is an enlarged side view thereof; and, FIG. 4 is a cross-sectional view taken along lines 4—4 of FIG. 2.

The track has been broken away in FIG. 1 to indicate indeterminate length.
